(57) **CLAIM**

The ornamental design for a set of fork, spoon and knife, as shown and described.

DESCRIPTION

FIG. 1 is a first perspective view of the first element of a set of fork, spoon and knife showing my new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of the second element of a set of fork, spoon and knife showing my new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a first perspective view of the third element of a set of fork, spoon and knife showing my new design;

FIG. 18 is a second perspective view of the third element thereof;

FIG. 19 is a front view of the third element thereof;

FIG. 20 is a back view of the third element thereof;

FIG. 21 is a left side view of the third element thereof;

FIG. 22 is a right side view of the third element thereof;

FIG. 23 is a top view of the third element thereof; and,

FIG. 24 is a bottom view of the third element thereof.
